PROCESS FOR MAKING TETRAETHYL LEAD

Hymin Shapiro, Detroit, and Earl G. De Witt, Ferndale, Mich., assignors to Ethyl Corporation, New York, N. Y., a corporation of Delaware

Application October 25, 1951, Serial No. 253,131

14 Claims. (Cl. 260—437)

1

This invention relates to an improved process for making tetraethyllead.

At present tetraethyllead is made commercially by reacting monosodium-lead alloy with ethyl chloride according to the following equation:

The yield of tetraethyllead on the alkali metal or sodium is around 88 per cent. Much effort and expense has been made by many previous workers in this field to improve this yield without changing the entire character of the process, but little success has been achieved. It should be noted that three atoms of metallic lead are formed which can be further treated in a separate and different process to produce tetraethyllead, or realloyed with sodium. Thus even though higher yields on a lead basis can be obtained by further treatment of the free lead produced, this does not solve the problem of obtaining higher yields on the alkali metal. Any loss in sodium effectiveness is wasted since the sodium values which do not produce tetraethyllead cannot be recovered economically, whereas the lead can be recovered readily and reused. Further, such wasteful use of sodium also consumes ethyl chloride which results in the formation of useless hydrocarbon by-products. Thus, this defect in the past present commercial process could stand improvement from the viewpoint of economics.

It is, therefore, among the objects of this invention to provide a process for substantially improving the yields of tetraethyllead based on the alkali metal used. A further object is to make tetraethyllead in high yields at lower temperatures and pressures and with less expensive equipment.

We have made the surprising discovery that this object can be accomplished by treating a ternary alloy of lead, sodium and potassium with ethyl chloride in the presence of a catalyst.

By this process we are able to increase the yield of tetraethyllead based on the alkali metal from 88 to as high as 98 per cent, a figure never before envisioned as attainable in this art.

Previously, many unsuccessful efforts have been made to find a catalyst to increase the ultimate yield of tetraethyllead from NaPb alloy above the level of 88 per cent normally reached commercially under optimum reaction conditions. Some organic compounds have been found which increase the rate of this alkylation reaction, but they do not raise the ultimate yield. In general, rate accelerators of this nature are

2

described in Patents Nos. 2,426,598; 2,464,397; 2,464,298; 2,464,399 and 2,477,465. It should be emphasized that while they accelerate the alkylation reaction, they have no noticeable effect upon the ultimate yield. Indeed, at temperatures below about 70° C., it was known that these compounds actually reduced the desired yields of tetraethyllead, in some cases by as much as 5 per cent or more.

10 In lieu of NaPb alloy in the reaction just referred to, it has been suggested that ternary alloys containing potassium, sodium and lead might be used. In this connection, see U. S. Patents Nos. 1,668,021 and 1,749,567. The use of such ternary alloys was believed to increase the yield of the desired tetraethyllead at lower temperatures above that which would be obtained under the same conditions with an NaPb alloy. From the experience of those familiar with this field in the use of accelerators for the reaction employing NaPb alloy, it was generally believed that they would exert a similar, depressing effect if employed with the ternary alloys. In other words, it was assumed that such accelerators would detrimentally affect the desired ultimate yields. As a result, investigators in this field carefully refrained from employing accelerators in the reaction involving the potassium, sodium and lead alloy. This is apparent from a careful consideration of the foregoing and other prior art patents.

15 As mentioned previously, potassium was added in small amounts to a sodium-lead alloy for production of tetraethyllead, but the alkylation was conducted at low temperatures, i. e. 12° to 45° C., and in the absence of a catalyst, and at long reaction times of at least 6 hours and usually around 24 hours. Even at these long reaction times the maximum yield obtained by such workers was only 85 per cent, which is lower than the yield obtained in the present commercial process. Such workers taught that low temperatures were desirable and that high temperatures were to be avoided. In confirmation of this, we have found that when the temperature is raised to 80° C. in the absence of a catalyst, the yield is only about 40 percent.

20 The earlier workers in this field were quite justified in operating at low temperatures. The optimum yields from the familiar sodium-lead alloy, NaPb, are obtained at temperatures of about 70° to 100° C. (depending on the other conditions of reaction), and when the temperature is raised much over 100° the yields fall off greatly owing to increased side reactions. Now, potas-

sium is considered by chemists to be more active than sodium, and prior workers properly reasoned that optimum temperatures for a ternary alloy containing potassium should be lower than for an alloy containing no potassium. They had no reason to suspect that higher temperatures would produce beneficial results, with or without a catalyst.

Not only did prior workers consider higher temperatures unnecessary, but, on the contrary, they deliberately sought to avoid them. They were seeking a low temperature process which did not involve expensive pressure equipment, and also they were not inclined to use a high reaction temperature on alloys containing a metal more reactive than sodium because these alkali metal-lead alloys are inherently dangerous.

Further it has been the experience of workers in this field that the addition of other reducing metals to the inter-metallic compound, NaPb, modifies its homogenous crystal lattice, and that on alkylation at normal operating temperatures of around 80° C. the resulting yield of tetraethyllead based on the total reducing metal content is actually lower than that obtained with the sodium-lead alloy alone. For example the best yield obtained when about one per cent of magnesium, calcium or sodium itself were added to the sodium-lead alloy, NaPb, was 64, 69, and 84 per cent respectively, under conditions where the yield from NaPb was 88 per cent. However, the yield from NaPb plus one per cent potassium under the same conditions was 92 per cent.

The findings of our invention are in surprising contrast to these prior results. This is in part shown by the data in Table I and in the figure, giving the tetraethyllead yield versus the reaction temperature for standard NaPb alloy and for our sodium-potassium-lead alloy, each with and without a catalyst. First, it is evident that the presence of a catalyst has a profound effect on the yield from our alloy, both at elevated and very low temperatures. This involves more than a mere increase in rate of alkylation, for at 80° C. the initial rate for the catalyzed reaction of our alloy is actually lower than that for NaPb, although both reactions go to completion in about the same time and the ultimate yield of tetraethyllead is considerably higher for our alloy. Moreover, as shown by the data in Table II, many of the organic compounds found to be effective catalysts for our reaction are different from those known to increase the rate of alkylation of NaPb. Second, it is evident that with a potassium alloy, the presence of a catalyst is never detrimental; on the contrary, it increases the yield of tetraethyllead over the entire temperature range. Third, the yield from our alloy with catalyst does not fall off at elevated temperatures as would have been expected, a fact of importance for commercial operation wherein the use of moderately high temperatures facilitates the removal of the heat of reaction.

To obtain the data given in Table I, a series of runs was made in which the conditions were the same except for the temperature and use of catalyst, said conditions being two hours reaction time, 7 theories of ethyl chloride (a theory being the amount of ethyl chloride required to react with the alkali metal according to the above equation), and sufficient pressure to maintain the ethyl chloride in liquid phase at the

reaction temperature employed. For the catalyzed test 0.2 per cent of acetone was used, based on the alloy charged.

The data so obtained are plotted on the figure, curves A and B being respectively catalyzed and non-catalyzed tests using the present commercial alloy, which consists of one atom of sodium to one atom of lead. It should be noted that in commercial practice curves A and B show that little difference in tetraethyllead yield is obtained at 60° C., and higher, between a catalyzed and a non-catalyzed reaction. On the other hand, at temperatures below 60° C. the non-catalyzed yield is higher than the catalyzed yield.

However, this is not the case for a sodium-lead alloy containing a small amount of potassium. Curves C and D represent the data we obtained when operating with an alloy, containing 1.5 weight per cent potassium, in which the atom ratio of total alkali metal to lead is 1 to 1, curve C being the results obtained on a catalyzed reaction and curve D the results obtained on a non-catalyzed reaction. It is to be specifically noted that, not only is the catalyzed yield higher than the non-catalyzed throughout the temperature range as contrasted with curves B and A for the standard sodium-lead alloy, but at temperatures below 40° C. and above 60° C. the improvement between the catalytic and non-catalytic yield is remarkable, entirely unexpected, and could not be predicted.

We believe that our high yields are realized because the conditions we use reduce the side reactions obtained previously and therefore permit a higher utilization of the reducing metals. In the present commercial process about 10 per cent of side reactions occur according to the following illustrative equation:

with ethane and ethylene obtained as by-products together with butane. This explains the hydrocarbon gases formed along with most lead ethylation reactions.

To support our belief that our yields are obtained at the expense of by-product formation, three different alloys containing 50 atom per cent lead and 50 atom per cent of alkali metal in which the weight per cent of potassium was 0, 1.25 and 1.5 were reacted for 2 hours at 80° C. with 7 theories of ethyl chloride in the presence of 0.2 weight per cent based on the alloy charged of an acetone catalyst. The yields of tetraethyllead based on the alkali metal were 89, 96, and 98 per cent respectively. Upon completion of the reaction and after removal of the tetraethyllead, the remainder of the reaction mass from each was analyzed for inorganic chloride. Based on such analysis the amount of ethyl chloride consumed in excess of that required to produce the tetraethyllead found, was 8.5, 2.0 and 1.0 per cent respectively. Thus it can be said that the by-product formation for the present commercial alloy is four to eight times that for our alloy.

Similarly when a sodium-lead alloy containing 1.5 weight per cent potassium was tested at a reaction temperature of 80° C., in the absence of a catalyst, the by-product formation as measured by above method was 8.5 times that obtained when using an acetone catalyst. Thus even using longer reaction times the non-catalytic yield can never reach the catalytic due to by-product formation.

Thus it is unescapable that the nature of our catalyzed reaction is radically different from any

of the prior teachings and it is surprising indeed that the alloy of our invention, when ethylated at temperatures between 0° and 100° C., and in the presence of a catalyst and even at relatively short reaction periods, could produce such amazingly and almost theoretical yields, i. e. as high as 98 per cent.

Our invention can be best understood by referring to the following working examples in which, unless otherwise noted, parts and percentages are by weight and the yield of tetraethyllead is based on the amount of alkali metal charged.

EXAMPLE I

To a suitable pressure reaction vessel equipped with cooling and heating means, charging means, and pressure release means were placed 100 parts of a ternary alloy containing equiatomic proportions of lead and alkali metals and in which the potassium content was 1.5 per cent. To this was added 193 parts (7 theories) of ethyl chloride and 0.2 weight per cent or parts of acetone based on alloy charged. The reaction was conducted for 2 hours at 80° C. and a pressure of 80 pounds per square inch. At the end of this period the tetraethyllead was separated from the other reaction products and was found to be 33.8 parts or 97 per cent yield.

Good results are obtained for potassium weight percentages between 0.1 and 5.0. This is illustrated by the following operations conducted under the same conditions as for Example I but in which the potassium content was 0.1, 0.5, 1.0, 2.0 and 3.0 per cent and in which the yield of tetraethyllead was 91, 92, 95.5, 95 and 92.5 per cent respectively. Thus over the entire range of our alloy composition the yield of tetraethyllead is higher than the present commercial operation and higher than that found previously. However for best yields a potassium content in the range between 1 and 2 per cent is preferred.

In the present commercial operation the yield of tetraethyllead falls off considerably if the content of sodium varies from 50 atom per cent. Thus the composition of the alloy is quite critical. This is not true to such a large extent when the amount of potassium taught herein is used. For our alloy within the range of 48 to 52 atom per cent for the total alkali metal content, the yield of tetraethyllead is always substantially above 90 per cent and good yields are obtained outside of this range. For example when the potassium content of three different alloys was kept constant at one weight per cent but the total alkali metal content was 49, 50 and 52 atom per cent, all other conditions being the same as for Example I, the tetraethyllead yield was 93, 94 and 91 per cent respectively, whereas when the same tests were repeated with an alloy containing no potassium the yield was always less than 90 per cent and at 53 atom per cent the yield dropped to 84 per cent. Likewise when the above three alloys containing potassium were employed at a 100° reaction temperature the yields were 94, 95 and 93 per cent respectively. However, it should be noted that the highest yields are obtained when the atomic ratio of alkali metal to lead is near 1 to 1. Also the sodium content should be between 5 and 35 weight per cent.

To obtain the advantage of our discovery the temperature range employed should be between 0° and 100° C. and preferably above 60° C. In other tests similar to Example I the catalyzed and non-catalyzed tetraethyllead yields for dif-

ferent temperatures for alloys with and without catalyst are shown in the following Table I.

Table I

Temperature	Percent Tetraethyllead Based on Alkali Metal in the Alloy Charged			
	Catalyst (Acetone)		No Catalyst	
	NaPb Alloy	NaPb+1.5% K	NaPb Alloy	NaPb+1.5% K
12	0	80	0	29
23	19	88	37	82
40	65	92	70	89
45	71	93	73	89
60	80	96	81	92
70	87	96	86	88
80	88	97	87	87
100	93	98	91	26

Likewise the reaction time can be varied within $\frac{1}{4}$ to 8 hours and high yields obtained. For example when using the same alloy and the same conditions as in Example I except that reaction times of $\frac{1}{2}$ hour, 1 hour, 3 hours and 6 hours were used, tetraethyllead yields of 95, 97, 96 and 98 respectively were obtained.

The amount of ethylating agent is not critical as long as it is used in an amount in excess over the stoichiometric requirement. Amounts between 1.05 and 30 theories can be successfully employed although we prefer to use an amount between 1.2 and 10 theories. Likewise the pressure is not critical but must be sufficient to maintain the ethylating agent in the liquid phase.

As mentioned previously a catalyst is essential to our invention. For example when the acetone catalyst of Example I was left out, the yield of tetraethyllead was only 37 per cent and the non-catalytic yield never reaches the yield obtainable with a catalyst. For a given temperature the non-catalytic yield may be improved at long reaction times, say 24 hours, unless excessive by-product formation prevents it, but such reaction times are impractical and would not be used commercially.

Catalysts other than acetone can be successfully employed in our invention. In general any of the compounds described as rate accelerators in Patents 2,426,598, 2,464,397, 2,464,298, 2,464,399 and 2,477,465 can be used. Other compounds, different from these in type, can also be used, for example, alcohols, ethers, aldehydes, amines, nitriles and peroxides, most of which are not even rate accelerators for the standard NaPb alloy and none improve the yield on such alloy to any extent, although all of them improve the yield on our potassium alloy.

Our catalysts are organic compounds soluble in ethyl chloride, containing a CO, a CN or a CS bond, having a boiling point range between -25° C. and 300° C., having a molecular weight between 30 and 250, having a density of less than 1.6, and having a hydrocarbon radical selected from the class of aliphatics and aromatics in which the number of carbon atoms is less than 15.

Among the catalysts which may be used for our invention are ketones including acetone, chloroacetone, acetophenone, benzophenone, cyclohexanone, diethylketone, methylethylketone, methylisopropylketone, dibutylketone, and phenylethylketone; esters including ethyl acetate, ethyl formate, vinyl acetate, diethyl carbonate, ethyl propionate, methyl acetate, dibutyl carbonate, ethyl acrylate, ethyl crotonate, benzyl acetate and ethyl benzoate; alcohols including ethyl

alcohol, methyl alcohol, capryl alcohol, benzyl alcohol, isopropyl alcohol, isobutyl alcohol, butyl alcohol, amyl alcohol, phenylethyl alcohol, and phenylpropyl alcohol; ethers such as allyl ether, propylene oxide, phenylethylene oxide, and 1,2-dimethoxyethane; aldehydes including isobutyraldehyde, benzaldehyde, furfuraldehyde, propionaldehyde, acetaldehyde and isoamylaldehyde; amines including isopropylamine, pyridine, triethylamine, methylamine, butylamine, isobutylamine, amylamine, diethylamine, and diisopropylamine; amides including butyramide, isobutyramide, phthalimide and acetonilide; nitriles including propionitrile, acrylonitrile, acetonitrile, butyrylnitrile and isobutyrylnitrile; anhydrides including butyric anhydride, benzoic anhydride, phthalic anhydride, acetic anhydride, propionic anhydride, and isobutyric anhydride; acetals including methylal (dimethoxymethane), ethylal (1,1-diethoxyethane), diethoxymethane, 1,1-dimethoxyethane, 1,1-dimethoxypropane, and 1,1-dipropoxyethane; peroxides including diteriarybutyl peroxide, isoctyl hydroperoxide, and benzoyl peroxide; aliphatic and aromatic nitro compounds such as nitroethane, nitrobenzene, nitropropane, nitromethane, nitrobutane, nitropentane and dinitrobenzene; esters of nitric and nitrous acids such as ethyl nitrite, amyl nitrate, isopropyl nitrite, benzyl nitrite, isoamyl nitrate, ethyl nitrate, butyl nitrate, propyl nitrate, and benzyl nitrate; acyl and aroyl halides including propionyl chloride, propionyl bromide, propionyl iodide, butyryl chloride, benzoyl chloride, and benzoyl iodide; isocyanates and isothiocyanates including phenylisocyanate and phenylisothiocyanate.

To illustrate the successful employment of our catalysts, tests were made identical to Example I with the results shown in the following Table II.

Table II

Weight percent	Catalyst Used	Tetraethyllead Yield	
		With Catalyst, percent	Without Catalyst, percent
0.2	Acetone	97	37
0.4	Chloroacetone	93	37

0.5	Phenyl Isothiocyanate	77	37
0.2	Iodine	83	37
0.5	Aluminum Chloride	89	37

The amount of catalyst employed generally is in the range of 1 to 1.

should be between 0.01 and 10 per cent based on the weight of alloy employed and preferably between .01 and 3 per cent. For example when acetone was employed as the catalyst in concentration of 0.2 and 1 per cent good yields are obtained in both cases, namely about 97 per cent in both cases.

However, the optimum concentration of catalyst depends on the catalyst used, the reaction temperature and the ratio of reactants, although substantial yields are obtained when the concentration of catalyst varies from the optimum within the above limits.

In the tests given herein the alloy was prepared as follows:

Weighed quantities of the three metals (sodium, potassium, and lead) were introduced into an iron bomb, under an atmosphere of nitrogen. The bomb was sealed, then heated slowly to 450° C., a temperature sufficiently above the melting point of the alloy formed from the combination of the 3 metals to insure complete mixing and alloying. The alloy was mixed at this temperature for 10 minutes, at which time the contents of the bomb were rapidly solidified by directing a rapid stream of cold water upon the outer surface of the bomb. By this means the solidification time of the alloy mass was between 1 and 5 seconds. The alloy was then removed from the bomb in a nitrogen atmosphere and comminuted to a convenient size for studying in subsequent reactions.

Similar tests have been made with equally good results using an alloy which was cooled very slowly during the solidification period, so that the crystallization time was very long (30-60 minutes).

However, our alloy can be prepared by any of the means found useful for preparing our present alloy. For example other methods can be employed as follows:

Conventional means employed in the present commercial process, wherein the alloy is cooled slowly upon vibrating bed casters.

Drum-type castings, wherein the alloy is very rapidly crystallized upon the cold surface of a drum which rotates beneath the surface of the melted alloy.

By dropping or spraying the molten alloy into a cooled chamber, or into a cold liquid, such as a hydrocarbon or ethyl chloride.

Other examples and modifications of our invention can be made based on the above teachings and coming within the following claims.

We claim:

1. A process for making tetraethyllead comprising reacting ethyl chloride with a ternary alloy of sodium, potassium and lead, in which the sodium content is between 5 and 35 weight per cent and the potassium content is between 0.1 and 5 weight per cent, in the presence of an organic lead alkylating catalyst selected from the group consisting of organic oxygen-containing and nitrogen-containing materials, at a temperature below about 100° C., under a pressure such that at the temperature used the ethyl chloride is maintained in the liquid phase, and for a time less than about 8 hours.

2. The process of claim 1 in which the total content of the alkali metal is between 48 and 52 atom per cent.

3. The process of claim 1 in which the amount of potassium is between 1 and 2 per cent and the atomic ratio of lead to total alkali metals

4. A process for making tetraethyllead comprising reacting ethyl chloride with a ternary alloy of sodium, potassium and lead in which the potassium content is between 1 and 2 weight per cent, the total sodium and potassium content is between 48 and 52 atom per cent in the presence of an acetone catalyst, at a temperature between 60 and 100° C., under a pressure such that at the temperature used the ethyl chloride is maintained in the liquid phase, and for a time between $\frac{1}{4}$ and 8 hours.

5. A process for making tetraethyllead comprising reacting ethyl chloride with a ternary alloy of sodium, potassium and lead in which the sodium content is between 5 and 35 weight per cent and the potassium content is between 0.1 and 5 weight per cent, under a pressure such that at the temperature used the ethyl chloride is maintained in the liquid phase, and for a time less than 8 hours, and in the presence of a lead alkylating catalyst.

6. The process of claim 5 further defined in that the catalyst is a ketone.

7. The process of claim 5 further defined in that the catalyst is acetone.

8. The process of claim 5 further defined in that the catalyst is methyl ethyl ketone.

9. The process of claim 5 further defined in that the catalyst is an ester.

10. The process of claim 5 further defined in that the catalyst is ethyl acetate.

5 11. The process of claim 5 further defined in that the catalyst is an alcohol.

12. The process of claim 5 further defined in that the catalyst is ethyl alcohol.

10 13. The process of claim 5 further defined in that the catalyst is an aldehyde.

14. The process of claim 5 further defined in that the catalyst is acetaldehyde.
